UNITED STATES PATENT OFFICE

HENRY ROBICHAUX, OF LAFAYETTE, LOUISIANA

BURNER

Application filed November 13, 1928. Serial No. 319,076.

This invention relates to an oil burner designed primarily for use in connection with fire boxes of locomotives although it can be used with other types of steam boilers.

It is an object of the invention to provide 5 a burner which cannot become clogged by foreign substances, utilizes steam and boiler pressure for atomizing the oil, and can be utilized to positively cut off the flow of oil so that there will be no waste due to leakage 10 while the burner is not in use.

A further object is to provide a burner in which the operating valves are located inside of the burner housing.

15 A further object is to provide a burner in which the steam and oil valves are controlled by the operation of a single element, thereby greatly simplifying manipulation of the valve mechanism.

20 A still further object is to provide a burner so constructed as to effect thorough mixing of the steam and oil within the burner prior to its discharge into the fire box, thereby preventing the formation of carbon on the 25 splash wall and the wall of the fire box.

With the foregoing and other objects in view which will appear as the description proceeds the invention resides in the combination and arrangement of parts and in the details 30 of construction hereinafter described and claimed it being understood that changes in the precise embodiment of the invention herein disclosed may be made within the scope of what is claimed without departing from the 35 spirit of the invention.

In the accompanying drawings the preferred form of the invention has been shown.

In said drawings,

40 Figure 1 is a vertical longitudinal section through the burner.

Figure 2 is a side elevation thereof.

Figure 3 is a section on line 3-3, Figure 2.

Figure 4 is a section on line 4-4, Figure 1, the valve being shown in plan.

45 Figure 5 is a section on line 5-5, Figure 1.

Figure 6 is a section on line 6-6, Figure 1.

Referring to the figures by characters of reference, 1 designates the upper section of the housing of the burner, this section consisting of a top plate having side flanges 2 con-

nected at one end by an end flange 3. The lower section 4 of the burner housing comprises a plate having side flanges 5 and an end flange 6. A housing 7 is formed on or connected to the plate of section 1 near the flange 3 and another housing 8 is connected to or formed integral with the plate of section 4 near its flange 6. Housing 7 opens into the section 1 through an aperture 9 while an aperture 10 maintains communication between housing 8 and the lower section 4. Housing 7 is adapted to be supplied with oil used for fuel while steam under boiler pressure is adapted to be supplied to the housing 8.

55 Interposed between the sections 1 and 4 is a partition plate 11 and the two sections 1 and 4 and plate 11 are held together securely by any suitable means, such as tie bolts 12 extending through the marginal portions thereof.

60 Mounted on the partition 11 at that end thereof remote from the housings 7 and 8 is a tapered plate 13 constituting a valve seat, this plate being held in position in any suitable manner, as by means of screws 13' extended laterally through the flanges 2 and into the sides of the plate 13.

65 To the bottom of the partition plate 11 is secured a tapered plate 14 likewise constituting a valve seat, this plate being located at that end of the partition remote from the housings 7 and 8. Plate 14 can be attached to the partition plate by means of rivets 15 or by any other suitable fastening devices. A plurality of ports 16 are formed within the partition 11 and valve seats 13 and 14, these ports being extended continuously through these parts and being inclined downwardly and forwardly toward that end of the burner remote from the housings. Thus oil will be free to flow through these ports from above the valve seat 13 to the space beneath the valve seat 14.

70 The housing section 4 is extended preferably a short distance forwardly beyond the section 1 and this plate supports a tapered slide valve 17 the active face of which is parallel with the lower face of the seat 14. From the forward or small end of this valve

is extended a tongue 18 on which are formed forwardly diverging spreading ribs 19. A short longitudinal slot 20 is formed in the inner end of the valve 17 and communicates with a transverse groove 21 in the bottom of said valve. In this slot is movably mounted a link 22 having a head 23 movably seated in the groove 21. Link 22 is pivotally connected at 24 to a crank arm 25 extending from the housing 8 through opening 10 and secured to a rock shaft 26 journaled in one side of the housing 8. As shown particularly in Figure 3 the bearing of this rock shaft is provided with a steam tight packing 27. To the outer end of the rock shaft 26 is attached an operating lever 28 having a short arm 29 in which is formed a longitudinal slot 29'. This lever can be actuated by any suitable means adjacent thereto or extending to a point remote therefrom.

Slidably mounted in the upper section 1 is a tapered valve 30 the inclined lower face of which is parallel with the upper face of the seat 13 and extends thereover. This slide valve is supported by guide ribs 31 or other suitable means provided for that purpose and has a longitudinal slot 32 in the inner end thereof communicating with a transverse groove 33 formed in the top of the valve. Movably mounted in the slot 32 is a link or connecting rod 34 having a head 35 movably mounted in the transverse groove 33. This link or connecting rod is pivotally attached at 36 to a crank arm 37 extending through the opening 9 and secured to a rock shaft 38 journaled in the housing 7. The bearing of the rock shaft is provided with a packing 39 to prevent leakage and the outer end of the shaft has an arm 40 secured thereto and provided with a longitudinal slot 41. A connecting pin 42 is adjustably secured in either slot 29' or slot 41 and is adapted to slide freely in the other one of these two slots. Thus when lever 28 is oscillated motion will be transmitted therefrom through pin 42 to the arm 40 so that the two shafts 26 and 38 will be rocked simultaneously. By adjusting the pin 42 longitudinally of the slots the relative movement of the shafts 26 and 38 can be varied as will be obvious.

The parts are so located and proportioned that when lever 28 is in one extreme position the two slide valves 17 and 30 will bear tightly against the active faces of the respective seats 14 and 13, thereby positively preventing leakage of oil from the section 1 and of steam from the section 4. By shifting lever 28 in the opposite direction the two shafts 26 and 38 will be simultaneously rotated thereby to withdraw the valves 17 and 30 from their seats. Thus a sheet of steam will be released promptly so as to escape between valve 17 and seat 14 and past the lower ends of the ports 16 thereby creating a downward suction through the ports. At the same time oil

delivered to the section 1 will be free to flow between valve 30 and its seat 13 and will be sucked downwardly by the escaping steam through the ports 16 into the space between tongue 18 and seat 14. This space, indicated at 43, constitutes a mixing chamber where the steam and oil are thoroughly commingled before the mixture is delivered at a high velocity over the spreading ribs 19. Obviously this mixture of oil and steam will be highly inflammable and by properly adjusting the pin 42 so as to produce correct relative movement of the two valves, the correct mixtures for producing the best results can be obtained.

It will be noted that steam under boiler pressure can be used and as the valves move bodily away from their seats there is no chance for foreign substances to clog the burner. Instead they will be blown out by the pressure within the burner. Furthermore, as the fuel will be thoroughly atomized before it can escape from the burner all danger of the delivery of unatomized fuel is eliminated and, consequently, there is no danger of the formation of carbon on the splash wall or the wall of the fire box. When the burner is not to be used the valves can be shifted tightly against their seats, thereby preventing leakage of oil or steam.

While the ribs 19 may be formed on the end portion of the tongue 18 they can, if preferred, be made on a part separate therefrom.

What is claimed is:

1. A burner including a housing, a partition therein, means for directing oil and steam into the housing at opposite sides respectively of the partition, inclined valve seats on the opposite sides respectively of the partition, tapered slide valves at opposite sides of the partition movable into and out of contact with the seats, an actuating element, and adjustable means shiftable by the actuating element for simultaneously moving the valves at predetermined relative speeds.

2. A burner including a housing, a partition therein, means for directing oil and steam into the housing at opposite sides respectively of the partition, inclined valve seats on the opposite sides respectively of the partition, tapered slide valves at opposite sides of the partition movable into and out of contact with the seats, means for simultaneously actuating the valves, and a spreading means adjacent the outer end of one of the valves in the path of fuel delivered past said valve.

3. A burner including a housing, a partition therein, means for directing oil and steam into the housing at opposite sides respectively of the partition, inclined valve seats on the opposite sides respectively of the partition, tapered slide valves at opposite sides of the partition movable into and out of contact with the seats, there being ports for maintaining communication between the valve seats, said

valves constituting means for controlling the flow of fluid through the ports.

4. A burner including opposed housing sections, a partition interposed therebetween and secured thereto for dividing the interior of the housing into an oil receiving portion and a steam receiving portion, a housing on each section opening into the adjacent portion of the section, operating means within each housing, an inclined valve seat on each side of the partition partly closing one end portion of the section in which it is located, the other end portion of the section being closed, a tapered slide valve in each section movable into and out of contact with the adjacent valve seat to shut off flow of fluid and to permit flow thereof, respectively, and a connection between each valve and the operating means in the housing in the section in which the valve is located.

5. A burner including opposed sections closed at one end and open at the other end, housings on the respective sections opening thereto and a partition interposed between and secured to the section for dividing the interior of the housing into separate fluid receiving spaces, of an inclined valve seat at the outlet end of each of said spaces, said valve seats being mounted on opposed faces respectively of the partition, there being ports extending through the valve seats for establishing communication between the spaces at opposite sides of the partition, a slide valve cooperating with each valve seat and movable thereagainst to close the port, and operating mechanisms within the housings and sections for actuating the respective slide valves.

In testimony that I claim the foregoing as my own, I have hereto affixed my signature.

HENRY ROBICHAUX.
